RADIO DIRECTION FINDER

Marcus G. Limb, Hyannis, Mass., assignor to Cape Cod Instrument Company, Hyannis, Mass., a corporation of Massachusetts

Application May 6, 1942, Serial No. 441,891

3 Claims.

(Cl. 250—11)

This invention relates to a multi-frequency radio direction finder, and particularly to the loop antenna thereof.

One of the objects of the present invention is to provide a novel directional loop-antenna which is so constructed that it can be made to resonate equally well on any one of a plurality of frequency bands, and at the same time maintain an optimum number of turns in the loop winding for the purpose of keeping the effective height of said winding at a maximum consistent with its diameter for a given frequency band.

This object is accomplished by making the loop antenna in two or more sections of substantially the same diameter, said sections preferably, though not necessarily, having a different number of turns, the values of the windings of the two loop sections being so related to each other that when all the loop sections are connected in parallel, the inductance of the entire loop-antenna is such that it will resonate effectively on the highest of a plurality of frequency bands, while when all the loop sections are connected in series, the inductance of the entire loop-antenna is such that it will resonate effectively on a lower frequency band. By introducing a loading coil into the series-connected loop sections, said loop-antenna will resonate on a still lower frequency band. In each case however the loop circuit has the optimum number of turns as it always includes both loop sections.

As stated above, the loop antenna may be made in more than two sections, and if the antenna has three or more sections, the said antenna may be adjusted to resonate effectively on still other frequency bands by connecting the antenna sections partially in parallel and partially in series.

By way of example and assuming that the loop antenna has two sections, these two loop sections may be so wound that when they are connected in parallel, the loop antenna will resonate effectively on a short wave frequency band of 1240 to 3000 kc. and when the two loop sections are connected in series, the loop-antenna will resonate effectively on the regular broadcast band of 540 to 1250 kc. while when the loading coil is added to the series-connected loop sections the antenna will resonate on a frequency band of from 220 to 550 kc. It is to be understood, however, that these particular bands are referred to simply for the purpose of illustration and that the invention is equally applicable for use in connection with other frequency bands.

In the drawings

Fig. 1 is a perspective view of a radio direction finder embodying my invention.

Fig. 2 is a diagrammatic view showing the circuits of the loop-antenna.

5 Fig. 3 illustrates a modification of the invention in which the loop-antenna is composed of three loop sections.

Fig. 4 is a view partially diagrammatic in nature illustrating constructional features of the loop antenna.

10 Fig. 5 is a side view of the supporting frame for the antenna with part broken out.

Fig. 6 is a section on the line 6—6, Fig. 5.

In Fig. 1 of the drawings, 1 indicates generally 15 the antenna loop structure of a radio direction finder, and 2 is the receiver which is provided with the usual controls 3. The loop-antenna structure 1 is mounted on the receiver housing for turning movement about a vertical axis as usual in devices of this class, and it is herein shown as having a compass 4 mounted therein, this being a structure similar to that shown in Patent No. 2,220,008, October 29, 1940.

20 In my improved antenna structure, the antenna loop is made in a plurality of sections which have substantially the same diameter, and which are herein shown as having a different number of turns. These loop sections are wound on a supporting frame 5 which is illustrated as comprising two annular side members 6 that are spaced apart and are connected by tie rods 7. In Figs. 2 and 4, the loop antenna has two sections which are indicated at 8 and 9 respectively, both sections being wound about the tie rods 7 of the 25 supporting frame and being situated between side members 6. The section 8 has a lesser number of turns than the section 9, the relative value of these two loop sections being determined by the character of the different frequency bands with which it is desired to use the instrument.

30 All the turns of both loop sections 8 and 9, however, have substantially the same diameter as they are wound on the same frame and they also have a common axis. The two ends 10 and 11 of the antenna loop circuit, which includes both 35 loop sections and thus has an optimum number of turns of substantially the same diameter are connected to the two sides 12 and 12a of the circuit leading to the receiver through the medium of a commutator of usual construction comprising the two collector rings 13 and 14, the collector ring 13 being connected to the circuit connection 10 of the loop circuit and the collector ring 14 being connected to the circuit connection 11 of said circuit. The circuit connections 12

and 12a of the receiver circuit are connected to the collector rings 13 and 14 through usual brushes indicated at 15, this being a well-known construction for maintaining the circuit connections between the loop circuit and the receiver circuit as the directional loop antenna of a radio direction finder is turned about its vertical axis in order to set it for minimum signal reception.

The receiver circuit, 12, 12a may be of any usual construction, that herein shown being equipped with the usual tuning condenser 16 and with the usual vacuum tubes, one of which, illustrated at 17, has its grid connected to the circuit connection 12a. This vacuum tube may either be a rectifying tube or an amplifying tube depending on the character of the receiving set, but since the invention does not refer to the receiving set per se, I have not thought it necessary to illustrate more of the receiving set than is shown in the drawings.

Means, such as a switch mechanism A, is provided for connecting the loop sections 8 and 9 either in parallel or in series, and, as stated above, the relative values of the two loop sections are such that when they are connected in parallel, the entire loop antenna has an inductance such that it will resonate effectively on a higher frequency band than when the two loop sections are connected in series.

While any suitable switch means may be employed for thus connecting the two antenna sections either in series or in parallel, I have herein shown a switch comprising two switch blades 18 and 19 pivotally mounted at 20 and 21 and adapted when swung in one direction to connect the contacts 20 and 21 with other contacts 22 and 23, while when swung in the other direction, the switch blade 18 will connect the contact 20 with the contact 24. The contact 22 is shown as being grounded on the chassis of the receiver and the shield of the loop as indicated at 25, and as also being connected to the low potential end of the loop section 8 by a circuit connection 26. The high potential or "hot" end of said loop section 8 is connected to the contact 24 by a circuit connection 27. The low potential end of the loop section 9 is connected with the contact 20 by a circuit connection 28 and the high potential or "hot" end of said loop section 9 is connected to the circuit connection 11, the latter also being connected to the contact 21 through a circuit connection 29.

When the switch A is thrown so that the switch blade 18 connects the contacts 20 and 22 and the switch blade 19 connects the contacts 21 and 23, the two loop sections 8 and 9 will be connected in parallel, the circuit connection through the loop section 8 including the ground 25, the circuit connection 26, the loop section 8, the circuit connections 27 and 30, to contact 23, switch blade 19 and circuit connection 29 to the circuit connection 11. The circuit through the loop section 9 is from the ground 25 through the circuit connection 31 to contact 22, thence through the switch blade 18 to contact 20 and circuit connection 28 to the loop section 9 and thence to the circuit connection 11.

When the switch A is reversed and the switch blade 18 is in a position to connect the contacts 20 and 24, then the loop sections 8 and 9 are connected in series, the circuit connection being from the ground 25, circuit connection 26, loop section 8, circuit connection 27, switch blade 18,

circuit connection 28 to loop section 9, and thence to the circuit connection 11.

The two loop sections 8 and 9 are so disposed on the supporting frame that the "hot" or high potential end of each loop section is situated in the central portion of the frame as indicated best in Fig. 4, the low potential end of each loop section being at the outer ends of the section, that is, adjacent the side members 6 of the supporting frame. The supporting frame and the windings are enclosed in a suitable metallic shield 33, and one advantage resulting from this manner of disposing the loop sections relative to each other is that effective capacity to the shield is reduced.

The switch mechanism A for connecting the loop sections either in parallel or in series may have any suitable or usual construction and may be mounted either on the loop itself or on the receiver 2. I will preferably, however employ a switch constructed so that the two switch blades 18 and 19 may be operated in unison from a single handle, and I will also preferably mount the switch on the loop itself as indicated in Fig. 1. This construction has the advantage that the collector ring assembly is simplified and the necessary conductors between the loop and the chassis are reduced to only a ground and one other wire.

As stated above, connecting the loop sections either in parallel or in series enables the antenna loop to be used effectively on either one of two different frequency bands. By introducing a loading coil into the loop circuit, when the two loop sections are connected in series, the loop inductance is so adjusted that the loop antenna can be effectively used on a frequency band of still lower frequency than when the loop sections are connected in series but are not used with the loading coil.

One way of connecting the loading coil into the circuit is illustrated in Figs. 2 and 4, this being done in connection with a band change switch B which may be installed in the receiver proper. This band change switch is shown as having two switch blades 34 and 35 connected in the circuit connection 12a, the switch blade 34 being adapted to engage any one of the three contacts 36, 37, 38 and the switch blade 35 being adapted to engage any one of the three contacts 39, 40, 41. The contacts 36 and 39 are connected by a circuit connection 42, the contacts 37 and 40 are connected by a circuit connection 43 and the contacts 38 and 41 are connected by a circuit connection 44 which has the loading coil 45 therein. The switch B should be operated in conjunction with the switch A so that when the switch A is adjusted to connect the loop sections 8 and 9 in parallel, the switch blades 34 and 35 will be in engagement with the contacts 36 and 39, thereby throwing a trimmer capacity 46 across the loop to enable it to be properly tuned.

When the switch A is adjusted to connect the loop sections 8 and 9 in series, then the switch blades 34 and 35 will be brought into engagement with the contacts 37 and 40 thereby throwing another trimmer capacity 47 across the loop. By swinging the switch blades 34 and 35 onto the contacts 38 and 41, the loading coil 45 will be thrown into the loop circuit and a third trimmer capacity 48 will be introduced in the circuit.

I have stated above that the loop antenna might be divided into more than two sections and in Fig. 3 there is illustrated a construction

in which said antenna is formed of the three sections 50, 51 and 52. These sections will be wound on the same supporting frame as in the construction shown in Fig. 4 and will therefore all be of the same diameter. The number of turns in each section may be varied as desired.

Where a loop made in three sections is employed, I propose to provide a loop switch by means of which the three sections can be connected either in series or in parallel or two of the sections may be connected in parallel but in series with the third section. This will provide an antenna loop which will operate effectively on four different frequency bands.

Any suitable switch mechanism may be employed for connecting the three loop sections in parallel or in series or partly in series and partly in parallel and as illustrative of a switch mechanism suitable for this, I have shown one including the switch blades 53, 54, 55 and 56. The switch blade 53 is adapted to engage either of the contacts 57 or 58, the switch blade 54 may be brought into engagement with the contact 59. The switch blade 55 may be brought into engagement with the contact 60 while the switch blade 56 may be engaged with either of the contacts 61 or 62. When the switch mechanism is set to connect the three loop sections 50, 51, 52 in parallel, the switch blade 53 will be brought onto its contact 58, the switch blades 54 and 55 will be closed onto the contacts 59 and 60, while the switch blade 56 is closed onto the contact 62. The circuit through the loop section 50 will include the circuit connection 26, loop 50, circuit connections 27 and 30, switch 54 and circuit connection 63 to the circuit connection 11. The circuit through the loop section 51 will include circuit connection 31, switch blade 53, circuit connection 28, loop 51, circuit connection 65, switch blade 56 and circuit connection 66, to the circuit connection 11.

The circuit through the loop section 52 will be circuit connections 31 and 67 to contact 60, switch blade 55, circuit connection 63 to loop section 52 and thence to circuit connection 11.

By closing the switch blade 53 onto the contact 57 and opening the switch 54, the loop sections 50 and 51 will be connected in series but in parallel with the loop section 52.

By further adjusting the switch so as to open the switch 55 and close the switch blade 56 onto the contact 61, all three loop sections will be connected in series.

Where a three-section antenna is employed, I propose to make the band change switch, which is indicated at B1 in Fig. 3, with four contact points as illustrated so that said switch may be set into four different positions, one for each of the four frequency bands for which the antenna loop may be adjusted.

The switch B1 is shown as having two switch blades 34a and 35a that may be connected to move in unison, the switch blade 34a being adapted to contact with the contacts 71, 36a, 37a, 38a, and the switch blade 35a being adapted to engage the contacts 72, 39a, 40a and 41a. The circuit connection connecting the contacts 38a and 41a has the loading coil 45a therein as in Fig. 2,

and the circuit connections are such that trimmer capacity of an appropriate amount may be thrown across the loop in the different positions of the switch blades 34a and 35a.

The more turns there are in a loop-antenna for a given frequency band, the stronger will be the received signal and the better the null indication.

By so making the loop that all the turns of all the loop sections are of substantially the same diameter and are all included in the loop circuit when the loop is adjusted to operate on any one of the various frequency bands, there is provided a loop-antenna having the optimum number of turns of the same diameter in the loop winding which keeps the effective height of the latter at a maximum for all of the frequency bands.

While I have shown the loop sections as having a different number of turns, yet the invention would not be departed from if said loop sections were made with the same number of turns as under some circumstances such a construction would operate efficiently.

I claim:

1. A directional loop antenna structure for a radio direction finder, said loop structure comprising a rotatable supporting frame, a loop antenna wound on said frame and comprising two loop sections having substantially the same diameter and having a common axis but having a different number of turns, a single shielding element enclosing both loop sections of said antenna, each loop section having its high potential side on the end thereof adjacent the other section and its low potential side at its outer end adjacent a wall of the shield, whereby the capacity between the antenna winding and the shield is reduced, and means for connecting said loop sections either in parallel or in series.

2. A loop antenna for a radio direction finder, said antenna comprising two loop sections, all the turns of both sections having the same diameter and having a common axis, one loop section having a greater number of turns than the other, a single shielding element enclosing both loop sections, the high potential end of each loop section being situated adjacent the high potential end of the other loop section and the low potential end of each loop section being situated adjacent a wall of the shield whereby the capacity between the antenna winding and the shield is reduced, and means for connecting said loop sections either in parallel or in series.

3. A loop antenna for a radio direction finder, said antenna comprising two loop sections, all the turns of both loop sections having substantially the same diameter and having a common axis, a single shielding element enclosing both loop sections of said antenna, the windings of said sections being arranged with the high potential ends thereof situated between the low potential ends, whereby said low potential ends are nearer the walls of the shielding element than the high potential ends, and means for connecting said loop sections either in series or in parallel.

MARCUS G. LIMB.
